UNITED STATES PATENT OFFICE.

JOHN BERG, OF CHICAGO, ILLINOIS, ASSIGNOR TO METAL SPECIALTIES MANUFACTURING COMPANY, OF CHICAGO, ILLINOIS, A CORPORATION OF ILLINOIS.

ELECTRIC CONNECTOR.

1,271,999.

Specification of Letters Patent.

Patented July 9, 1918.

Application filed July 20, 1917. Serial No. 181,893.

To all whom it may concern:

Be it known that I, JOHN BERG, a citizen of the United States, residing at Chicago, in the county of Cook and State of Illinois, have invented a new and useful Improvement in Electric Connectors, of which the following is a specification.

This invention relates particularly to electric-connectors, such as are used for connecting electric-conductors together, or for connecting electric-conductors to any electrical device, such as an electric-lamp, or other electrical device. The primary object is to provide a connector with an improved switch device, whereby the circuit may be established or broken with facility, as desired.

The invention may be employed very advantageously in connection with either a dash-lamp or an exploring lamp for automobiles.

The invention is illustrated in its preferred embodiment in the accompanying drawing, in which—

Figure 1 represents an elevational view of a dash-lamp carried by a connector equipped with my improvement, the connector being mounted on a dash, which is shown in section; Fig. 2, a bottom plan view of the connector and the dash-lamp shown in Fig. 1; Fig. 3, a vertical sectional view taken as indicated at line 3 of Fig. 2; Fig. 4, a sectional view taken as indicated at line 4 of Fig. 3; Fig. 5, a sectional view taken as indicated at line 5 of Fig. 3; Fig. 6, a similar sectional view, looking in the opposite direction as indicated by the arrows numbered 6 in Fig. 3; and Fig. 7, a sectional view illustrating a modification.

Referring to Figs. 1 to 6, inclusive, A represents the improved connector, which, in this form, is adapted to be mounted upon an automobile dash, and which is shown equipped with a removable guard A¹, which serves also as a reflector; B, a lamp or electric bulb removably mounted in one end of the connector A; and C, a dash of an automobile body, to which the connector A may be conveniently attached.

In the construction illustrated, the connector A comprises a metal shell or sleeve 1, one end of which is provided with a bayonet slot 2 for securing the lamp B, and the other end of which is fitted with a plug 3, which

is equipped with spring-contacts; and a revoluble switch-disk 4 located in the shell 1 between the lamp and the plug 3, said switch-disk being provided with conductors 4^a which extend therethrough and have extremities which project somewhat beyond the ends of the disk and serve as contact members.

The switch-disk 4 preferably comprises a disk of hard-rubber having two eccentrically located perforations in which the members or contact-posts 4^a are tightly fitted. The members 4^a preferably comprise short brass rod-sections, which have rounded ends forming suitable contacts. Extending through the disk 4 is a stud or pin 5, which works in segmental median slots 6 with which the shell 1 is provided at diametrically opposite points. The pin 5 is equipped with an actuating handle 5^a.

The shell 1 is, in the form being described, equipped at one end with a flange 1^a, which is adapted to be secured to the dash C, and is equipped at the opposite end with an annular holder 1^b which receives snugly the rear end of the reflector or guard A¹.

The lamp B has its shank equipped with the usual lateral studs 7, which engage the bayonet slots 2 of the shell 1; and the shank has at its inner end the smooth contacts 7^a.

The plug 3 preferably comprises a disk 3^a of insulating material, such as hard-rubber; a pair of segmental spring-contact members 3^b disposed adjacent to the switch-disk 4 and having shanks extending through slots 90 in the disk 3^a; and a sleeve 3^c of insulating material interposed between the shanks of the members 3^b and the shell 1. The disk 3^a and the sleeve 3^c are secured within the base portion of the shell 1 by a pin 8. It will be understood that the shanks of the contact-members 3^b afford conductors which extend through the plug 3, and the rear ends of the said shanks are equipped with sockets 3^d adapted for connection with conductors.

The flange 1^a at the base end of the shell 1 is suitably formed from a disk of metal, which is perforated and provided with a sleeve-portion which is rigidly fitted on the end-portion of the shell. The holder 1^b which receives the guard A¹ is likewise formed from a disk of metal, which is per-

forated and provided with a sleeve-portion which is rigidly fitted on the front end of the sleeve or shell 1.

As has been indicated, the switch-disk 4 is interposed between the lamp and the plug 3. The contact-members of the switch-disk are adapted to register with the contact-members 3^b, and with the contact-members of the lamp, as shown in Fig. 3. By turning the switch-disk from the position shown in Fig. 5, the pin 5 moving through the segmental slots 6, the contact-members 4^a will be thrown out of registration with the contact-members 7^a of the lamp. The spring contact-members 3^b are of segmental form, and are inclined or sloped away from the end of the plug 3^a. These spring contact-members are under sufficient pressure to hold the switch-disk firmly against the base end 20 of the lamp. The slots 6 are of sufficient width to permit a certain amount of longitudinal movement of the switch-disk within the shell 1. Preferably, however, each slot 6 is provided at one side of its end-portions 25 with recesses 6^a, which are separated by a curved edge 6^b, the convexity of which is preferably sufficient to prevent accidental shifting of the switch-disk. The stud 5 should be so disposed as to be substantially 30 out of contact with the walls of the recesses 6^a, in order that the spring-contacts 3^b may serve effectively to crowd the switch-disk against the base end of the lamp.

In the modification shown in Fig. 7, the construction is similar to that described, except that the shell, here designated 1^c, is fitted at one end with a plug 3^c, equipped with spring-pressed plunger contacts 3^e; and the flange 1^a for attachment to a dash 40 is omitted. The switch-disk 4 is provided, as in the first described construction. In this modification, also, the plug 3^c projects from the shell and is equipped with lateral studs 9 adapted to engage the bayonet slots 45 10 of a connector 11, which is attached to conductors 12. This enables the lamp to be used as an exploring lamp; and it may be disconnected from the connector 11 and inserted in any usual connector applied to a dash, so that the lamp may also be used as 50 a dash-lamp.

The construction described is simple and thoroughly adapted to its purpose. The switch-disk is of exceedingly simple form and not liable to get out of order. It may be readily introduced into the shell and the pin 5 carrying the actuating-handle 5^a may then be thrust through a close-fitting perforation in the switch-disk, the stud also 60 extending through the segmental slots 6 of the shell.

The foregoing description has been given for clearness of understanding, and no un-

necessary limitation should be understood therefrom.

65

What I regard as new, and desire to secure by Letters Patent, is:

1. A device of the character set forth, comprising an integral shell provided at one end with bayonet-slots and provided also 70 with a median lateral segmental slot, an annular guard-holder encircling and embracing the bayonet-slot end of said shell, a plug secured in the other end of said shell and equipped at its inner end with spring- 75 contacts, and a switch-disk of insulating material within the median portion of said shell and equipped with an actuating handle extending through said segmental slot, said switch-disk being adapted to oscillate with 80 relation to said plug and having contact-posts extending therethrough and adapted to engage said spring-contacts.

2. A device of the character set forth comprising a shell provided with median 85 lateral segmental slots having recesses at one side of their end-portions, a lamp having a shank secured in one end of said shell and equipped at the inner end with contacts, a plug secured in the other end of said shell 90 and equipped with spring-contacts, and an interposed rotatable switch-disk of insulating material adapted to oscillate with relation to both said lamp-shank and plug and provided with a lateral actuating stud which 95 is normally out of engagement with the walls of said slots and provided also with metal contact-posts extending through said disk and having extremities at one end adapted to engage said spring-contacts and 100 extremities at the other end adapted to be thrown into and out of registration with said lamp-contacts by oscillation of said switch-disk.

3. A device of the character set forth 105 comprising a shell provided with a median lateral segmental slot, said shell equipped at one end with a flange for attachment to a dash and equipped at the other end with a removable lamp-guard, said shell having 110 also bayonet slots at the end which carries said lamp-guard, a lamp having a shank equipped with lateral studs engaging said bayonet slots and provided at its inner end with contacts, a plug secured in the opposite 115 end of said shell and equipped with spring-contacts, and an interposed switch-disk of insulating material adapted to oscillate with relation to both said lamp-shank and plug and provided with contact-posts extending 120 therethrough, said switch-disk equipped with a lateral actuating stud working in a segmental median slot with which said shell is provided.

JOHN BERG.
